UNITED STATES PATENT OFFICE.

FRANK N. REEVES, OF WOODENSBURG, MARYLAND, ASSIGNOR TO WESTERN ELECTRIC COMPANY, INCORPORATED, OF NEW YORK, N. Y., A CORPORATION OF NEW YORK.

SELECTIVE-SWITCH-CONTROLLING SYSTEM.

Application filed June 21, 1924. Serial No. 721,382.

This invention relates to a telephone exchange system and more particularly to selective switches for use in a machine switching system.

It is an object of this invention to provide an improvement in selective switch control.

In machine switching systems, various types of selective switches are used to associate a calling with a called line. One type of selective switches are equipped with a plurality of movable brush members, each brush member being associated with a particular bank of terminals. These selective switches are directed to select a particular bank of terminals by an operation known as brush selection. This operation constitutes the positioning of a particular one of the plurality of movable brush members in such manner that the contacts of the brush member may be tripped. The tripping operation controls the association of the particular brush contacts with the first set of terminals in a bank. Upon the completion of brush selection, the selective switch is operated to select a group of terminals within the bank over which the tripped brush member may hunt for an idle line.

Each bank in a frame is usually divided into several groups of terminals in a uniform manner, with a special set of terminals above each group known as the overflow terminals. A commutator, common to the plurality of banks in a frame, is equipped with segments corresponding in location to the overflow terminals, to limit the hunting scope of the movable brush member. Large groups of lines extending to particular offices require a plurality of groups of terminals in a bank and plurality of groups are therefore combined into one group known as an office group. In such office groups, it is desirable to connect lines to the intermediate unused overflow terminals. Within the knowledge of the applicant, this has not been done heretofore, since the office groups could not be economically arranged in the same manner in each of the plurality of banks and means were not provided to control the overflow segments of the commutator to make it flexible for the control of the selective switch when its movable brush members were associated with any of the plurality of banks of terminals.

A feature of this invention is in the provision of means for controlling selective

switch operation in accordance with the operation of a particular brush as associated with a particular bank of terminals.

This and other features of the invention will be apparent in the following description taken in connection with the accompanying drawings.

While the invention has been disclosed as particularly adapted for the operation and control of selective switches in a machine switching system, it is apparent from the following description that the invention has a wider utility and that by slight modifications, it could be adapted for control of apparatus in other types of systems.

With reference to the drawings, Fig. 1 illustrates diagrammatically a subscriber's station 100, line switch 101, district selector switch 102, and sender 103. Fig. 2 illustrates an office selector switch and associated circuits arranged to disclose the invention. Fig. 3 shows a set of brushes of the switch 220 with the brushes in the normal untripped position. Fig. 4 shows a set of brushes in the tripped position.

Description of apparatus.

The apparatus shown in Fig. 1 is of a well known type and is the same as disclosed in the Patent 1,395,977, issued Nov. 1, 1921 to F. A. Stearn and F. J. Scudder. Switch 260 is of the step-by-step type operated by the energization and deenergization of magnet 261. Switch 200 is of the well known sequence switch type. Selective switch 220 is of the same general type shown in Patent 1,123,696, issued January 5, 1915 to E. B. Craft et al. The brush members of the selector switch are equipped with a contact to establish a circuit for selective switch control when the brush members are brought into engagement with the terminals of a multiple bank. Commutator 270 is equipped with a special segment 243 not ordinarily used with such commutators. The conducting segments of commutator segment 242 control the operation of switch 260 to position its brush assembly for cooperative control of the selective switch in conjunction with the contact associated with the movable brush member.

The brush set 255 has been shown in Fig. 3 to illustrate the brush assembly and associated contact and its relation to the terminals of the multiple bank. In this illus-

tration, the trip finger 249 has not engaged the lever arm 248 to cause its operation. This set has been shown in Fig. 4 to illustrate the brush assembly and associated contact after trip finger 249 has engaged lever arm 248 and caused its operation to associate the brushes with the terminals of a multiple bank and to close the contact associated therewith. Brush set 255 illustrates the one of a plurality of such brush sets assembled in a selective switch that has been selected to be brought into engagement with the terminals of a multiple bank.

15 General description.

In accordance with the invention selective switches of a machine switching office are associated with frames sub-divided into banks of terminals, the banks in turn being sub-divided into groups. Each selective switch has one set of brushes for each bank of multiple terminals in order that a particular brush set may be associated with a particular bank and is first directed by a sender to position the particular brush set for cooperation with its bank of terminals. After a particular brush set has been properly positioned, the brush members of the brush set are tripped to bring them into association with the terminals of the bank. Upon the completion of brush selection, the selective switch is directed by the sender to make group selection to position the selected brushes upon the first terminals of a selected group. The selective switch is then operated to cause the particular brush set to move upward to select an idle line.

Groups of lines extending to distant offices are of various sizes and when groups of the same number of terminals are distributed over a bank of terminals, the hunting for an idle line is limited to that group. It often happens that all of the trunks in one group may be busy but there are trunks in a different group to the same office which are not busy. An overflow terminal is used at the top of each trunk group to arrest the upward movement of the selective switch and thus arrest its hunt for an idle line. In order to eliminate certain overflow positions in large trunk groups and use the positions for lines extending to a distant office, this invention provides a means whereby the overflow positions may be flexible, any one of which will be used for lines or overflow in accordance with the strapping of the terminals associated with the brushes of switch 260.

At the time that the brush members are brought into engagement with the terminals of the bank, a contact associated with the brush set is closed to establish control of the overflow terminals in that particular bank. When the selective switch has been arrested with its tripped brushes upon the first ter-

minals of a particular group, apparatus of the selective switch is controlled through this contact to designate the hunting limit for the selective switch in that particular office group.

70

Detailed description.

This description includes only a summary of the line switch, district selector and sender in order not to encumber it with details which are the same as disclosed and described in the aforementioned patent No. 1,395,977 to F. A. Stearn et al.

75

Let it be assumed that a subscriber at station 100 has removed the receiver from the switchhook preparatory to initiating a call. Line switch 101, district selector switch 102 and sender 103 are thus associated as shown in Fig. 1 and relay 110 is operated. The subscriber now operates the dial in accordance with the number of the line wanted. The operation of the dial actuates relay 104 of the sender 103 over a circuit extending from grounded battery through the winding of relay 104, lower contact of cam 112, lower contact of relay 110, contact of dial, upper contact of relay 110, lower contact of cam 111 to ground through balancing coil 108. Relay 104 is operated and released upon each interruption of the dial contacts to set the register switches of the sender. When the register switches have been set, the sender is advanced to a position for associating the district selection switch 102 in a manner to control its upward movement for brush and group selection. Upon the completion of group selection, brushes 121, 122 and 123 are brought into engagement with a bank of terminals associated with office selector switches and the district selector switch is positioned to control the upward movement of its associated brushes in such manner that an idle office selector switch is selected. Upon the selection of an idle office selector switch, such as shown in Fig. 2, the district selector 102 advances its sequence switch to position 10 in which position the sender 103 may control the selective operation of the apparatus shown in Fig. 2 in accordance with the setting of the register switches.

80

Upon the association of brushes 121, 122 and 123 with terminals 124, 125 and 126, the fundamental circuit is established to operate relay 271 and stepping relay 107. This circuit may be traced from grounded battery through the right winding of relay 271, lower contacts of cam 210, conductor 272, terminal 126, brush 123, lower contact of cam 115, windings of the polarized relay 105 and stepping relay 107, contact of counting relay 106, upper contact of cam 116, brush 122, terminal 125, conductor 273, right upper and left lower contacts of cam 203 to ground. The current flow in the cir-

cuit traced is not in the proper direction to operate polarized relay 105. The operation of relay 271 establishes a circuit to energize sequence switch magnet 201 from ground-
 5 ed battery through the winding of magnet 201, left lower contact of cam 212 to ground through the right outer contact of relay 271. Sequence switch 200 now rotates from position 1 to position 2. The operation of re-
 10 lay 271 further establishes a locking circuit for itself from grounded battery through its right winding and right inner contact, right lower contact of cam 207, conductor 272 and thence to ground over the fundamental
 15 circuit previously traced. Relay 271 is thus maintained in an operated position until the fundamental circuit is opened at the contact of counting relay 106. In position 2 of the sequence switch 200, a circuit is estab-
 20 lished to energize the up-drive magnet 222 from grounded battery through the winding of this magnet, upper contact of cam 212 to ground through the right outer contact of relay 271. The selector switch is now driven
 25 in an upward movement and brush 240 is advanced over commutator 244, which has conducting and non-conducting segments. The initial engagement of brush 240 with commutator 244 establishes a circuit to shunt
 30 the stepping relay 107 in the sender by the association of a ground with the fundamental circuit. This may be traced from ground through the lower contact of cam 213, brush 240, commutator 244, left upper
 35 and lower contacts of cam 210, and thence to a junction point with the fundamental circuit to cause a release of the sender stepping
 40 relay and to maintain relay 271 in an operated position. The operation and release of the sender stepping relay 107 operates counting relays in the sender circuit in a well known manner. When a number of counting relays have been operated in accordance with the setting of the sender register, the
 45 fundamental circuit is opened at a contact of the O' counting relay 106. The holding circuit for relay 271 is thus opened to cause its release. The release of relay 271 opens the energizing circuit for up-drive magnet
 50 222 to arrest the upward movement of the brush members and commutator brushes. The release of relay 271 further establishes an energizing circuit to rotate sequence switch 200 from position 2 to position 3.
 55 This circuit may be traced from grounded battery through the winding of sequence switch magnet 201, upper left contact of cam 209 to ground through the right outer normal contact of relay 271. During the rotation of the sequence switch, the sender 103 has operated to re-position its apparatus and release the counting relays.
 60 When the sequence switch 200 rotates to position 3, the fundamental circuit is again established to operate relays 271 and 107 in

the manner previously described for the establishment of circuits for office group selection. The locking circuit for relay 271 is again established as previously described. The operation of this relay establishes an
 65 energizing circuit to rotate sequence switch 200 from position 3 to position 4. This circuit may be traced from grounded battery through the winding of magnet 201, left lower contact of cam 212 to ground through the right outer contact of relay 271.

In positions 3 and 4 of sequence switch 200, a circuit is established to energize trip magnet 223 from grounded battery through the winding of magnet 223 to ground through the right lower contact of cam 211. The energization of trip magnet 223 rotates the tripping spindle 257 to engage the trip finger such as 249 with a lever arm such as 248. A plurality of movable brush members such as 255 and 256 equipped with cam levers such as 248 are assembled into each selective switch. The brush selection previously described is for the purpose of bringing the movable brush sets into such relation with the trip fingers of the tripping spindle 257 that only one of a plurality of trip fingers will engage the lever arm of one brush set. With sequence switch 200 in position 4, and relay 271 in an operated position, a circuit is established to energize up-drive magnet 222 from grounded battery through the winding of the up-drive magnet, upper contact of cam 212 to ground through the right outer contact of relay 271. The energization of up-drive magnet 222 drives the brush assemblies in an upward movement. During this upward movement, the trip finger 249 actuates the particular lever arm 248 to associate the brushes with the terminals of the bank multiple. The tripping of the brushes also effects the closure of a contact such as 224 the utility of which will be described later.

Upon the upward movement of the switch shaft, commutator brush 239 is engaged with commutator 243 to establish a shunt to intermittently release the stepping relay in the sender, thus causing the operation of the sender counting relays. Upon the operation of the O' counting relay 106, the holding circuit for relay 271 is opened to cause its release. The release of relay 271 opens the circuit for energizing up-drive magnet 222 and thus arrests the upward movement of the switch shaft and the commutator brushes.

Let it be assumed that brush set 255 was tripped as hereinbefore described and that brushes 225, 226 and 227 are now associated with the first terminals of a group of lines extending to a particular office. Also that the contact 224 is closed. The office circuit, Fig. 2 is thus prepared to hunt for an idle line extending to that particular office.

During the previously described upward movement of the switch shaft for group selection, brush 238 engaged commutator 242. Upon each association of brush 238 with a 5 conducting portion of commutator 242 magnet 261 is energized to attract its armature to prepare for a forward stepping of brushes 263, 264 and 265 and upon each engagement of brush 238 with an insulating 10 portion of commutator 242, opens the circuit of magnet 261 to cause the release of magnet 261 and the step by step advance of switch 260. During the engagement of brush 238, with a conducting portion of the 15 commutator, the circuit for energizing magnet 261 may be traced from grounded battery through its winding, commutator 242, brush 238 to ground through the lower contact of cam 213. When this circuit is 20 opened, magnet 261 releases to rotate the brush assembly 263, 264 and 265 one step. In this manner each engagement of brush 238 with conducting and non-conducting portions of commutator 242 advances the 25 brush assembly of switch 260 one step. Commutator 243 matches commutator 242 with relation to the number of conducting and non-conducting portions. These commutators are made with a comparatively 30 large number of sub-divisions in order that the line grouping may be made more flexible. A group of lines extending to an office may include one or a plurality of the sub-divisions and this invention proposes to mark 35 the size of the groups in the various banks of terminals through the association of switch 260 with commutator 242 which is common to all banks.

It will be noted that certain contacts associated with brushes 264 and 265 are strapped and the straps are associated with 40 relay 270. The number of contacts between the terminals that are strapped indicates the size of a group of trunks since each contact represents one step of switch 260 which is operated upon the association of brush 238 with a conducting portion of commutator 242. Switch 260 is started from its 45 normal position for all selections and is stepped to the first terminal of a certain office group during group selection.

Since it has already been assumed that the brush set 255 is the one used for this selection, contact 224 prepares a circuit path 50 through brush 265 and its associated contacts which is not effective until the sequence switch arrives in its sixth or trunk hunting position. Let it further be assumed that during group selection brush 265 was rotated to its seventh position which is not strapped to relay 270.

It will be remembered that upon the completion of group selection, relay 271 is released. The release of relay 271 establishes 55 a circuit to rotate sequence switch 200 from

position 4 to position 5. This circuit may be traced from grounded battery through the winding of magnet 201, left upper contact of cam 209, to ground through the right outer normal contact of relay 271. In position 5, a circuit is established to operate relay 271 from grounded battery through its left winding to ground through the lower contacts of cam 203. The operation of relay 271 establishes a circuit to further rotate the sequence switch from position 5 to position 6. This energizing circuit may be traced from grounded battery through the winding of magnet 201, left lower contact of cam 212 to ground through the right outer contact of relay 271. Upon the rotation of the sequence switch from position 5 to position 6, the energizing circuit for relay 271 is opened at the left lower contact of cam 203. Relay 271, however, is maintained in an operated position by a locking circuit, if the first terminal of the group is characterized by a busy ground. This holding circuit may be traced from grounded battery through the right winding, right inner contact and left contact of relay 271, lower contact of cam 206, right outer normal contact of relay 270, brush 225 to ground upon the sleeve terminal of the busy line. This holding circuit is further established from the right contact of relay 271 through the upper contact of cam 207 to the busy ground as previously traced.

Let it be assumed for this description that all of the lines in this group are busy. The continued energization of relay 271 establishes an energizing circuit for up drive magnet 222 from grounded battery through the winding of magnet 222, upper contact of cam 212 to ground through right outer contact of relay 271. During the upward movement of the selector switch shaft, brush 238 is associated with conducting portions of commutator 242 to further rotate the brush assembly of switch 260. Each of such engagements advances brush 265 one step as hereinbefore described. When brush 265 has advanced two steps, it is associated with the ninth position terminal which is connected to the winding of relay 270 to complete a circuit for its operation. This circuit may be traced from grounded battery through the winding of relay 270, brush 265 and its associated contact, contact 224 to ground through the right upper contact of cam 211. Relay 270 establishes a locking circuit for itself through its left contact to ground through the lower contact of cam 208 and in attracting its right outer armature opens the holding circuit for relay 271 to cause its release. The release of relay 271 opens the energizing circuit for the up drive magnet 222 to arrest the upward movement of the switch shaft and the commutator brushes. The circuit established through 125

the right inner contact of relay 270 will be described later. The release of relay 271 establishes a circuit to rotate the sequence switch from position 6 to position 7 from 5 grounded battery through the winding of magnet 201, left upper contact of cam 209 to ground through the right outer normal contact of relay 271. In sequence switch position 7, a circuit is again established to energize 10 relay 271 from grounded battery through its left winding to ground through the lower contacts of cam 203. The operation of relay 271 establishes a circuit to rotate the sequence switch to position 8. This circuit 15 may be traced from grounded battery through the winding of magnet 201, left lower contact of cam 212 to ground through the right outer contact of relay 271. A holding circuit is established for relay 271 20 from grounded battery through its right winding and right inner contact, left lower contact of cam 207, terminal 124, brush 121, contact of cam 117 to ground through the contact of relay 130 which is in an operated 25 position. It will be remembered that the sequence switch of the district selector Figure 1 is in position 10.

Since all of the trunks to the particular office are busy, the subscriber must be notified 30 that the wanted line cannot be obtained. With sequence switch 200 in position 8, relay 271 operated, and brush 240 resting on an overflow segment of commutator 244 which matches the segments of commutators 242 35 and 243, a circuit is established to energize magnet 201 from grounded battery through its winding, right upper contact of cam 209, right inner contact of relay 270, commutator 244, brush 240 to ground through the lower 40 contact of cam 213. The sequence switch now rotates from position 8 to position 9 under the control of the circuit traced and from position 9 to position 11 under the control of master contact 202. In sequence 45 switch position 11, a circuit is established to operate polarized relay 105 in the sender 103. This circuit may be traced from grounded battery through the left winding of relay 271, right contacts of cam 203, conductor 50 273, terminal 125, brush 122, upper contact of cam 116, contact of relay 106, winding of relay 107, winding of relay 105, lower contact of cam 115, brush 123, terminal 126, conductor 272, left contacts of cam 210, commutator 244, brush 240 to ground through the lower contact of cam 213. It will be 55 noted that the direction of current flow is opposite to that used for the control of the selective switch Figure 2, and is in the proper direction to operate the polarized relay 105 in the sender. The operation of relay 105 advances the sender apparatus in the manner described in the aforementioned Patent 1,395,977 to F. A. Stearn et al. and 60 the advance of the sender controls the dis- 65

trict selector 102 in such manner that its sequence switch is advanced to position 16. In position 16 of the district selector, a tone circuit is associated with the tip and ring conductors by induction from the left to the 70 right winding of coil 118. This may be traced from grounded battery through tone repeating coil 118, condenser 119, contacts of cam 118, right lower winding of repeating coil 120, condenser 130, right upper winding 75 of repeating coil 120 to ground through contact of cam 114. This tone is carried by induction into the left windings of repeating coil 120 and is thus transmitted to the calling subscriber as an audible signal indicating 80 that the called line cannot be reached. The subscriber restores the receiver to the switch-hook and the apparatus of the district selector and sender are restored to normal.

The rotation of the district sequence switch out of position 10, opens the holding circuit for relay 271 to cause its release. A circuit is thus established to rotate sequence switch 200 from position 11 to position 18. This circuit may be traced from grounded 85 battery through the winding of magnet 201, left upper contact of cam 209 to ground through the right outer normal contact of relay 271. Upon reaching position 18, a circuit is established to energize the down drive 90 magnet 221, from grounded battery through the winding of said magnet to ground through the contacts of cam 213. The selector switch 220 is now restored to its normal position and brush 239 is associated with 95 commutator 246. A circuit is thus established to energize the sequence switch to restore to normal which may be traced from grounded battery through the winding of magnet 201, lower contact of cam 209, commutator 246, brush 239, to ground through 100 the lower contact of cam 213. In positions 18 to 1 of the sequence switch, a circuit is established to restore switch 260 to normal by the energization of magnet 261. This 105 circuit may be traced from grounded battery through the winding of said magnet, self-interrupting contact 262, brush 263 and its associated contacts to ground through the upper contact of cam 208.

By the provision of a separate arc and associated brush such as 264 for each of the five brush banks of the selector the size of the groups in each bank may be varied by changing the strapping in the arc of switch 110 120 260 pertaining to such bank.

It is apparent from the foregoing that a control circuit established when selector switch brush selection takes place, may be used to control the hunting scope of a movable brush set in search of an idle line extending to a particular office. While the invention discloses means for controlling the extent of trunk hunting and thus the size 125 of trunk groups through the flexible location 130

of overflow terminals at various points in the banks of selective switch mechanism, it is not intended that the invention shall be limited to the control of office grouping since it has a wider utility and may be used for any form of control individual to each of a plurality of bank selecting means.

What is claimed is:

1. In a selector switch, a plurality of brush sets, banks of terminals associated with said brush sets respectively, the brushes of said brush sets being normally out of engagement with their associated bank terminals, means for bringing any one of said brush sets into engageable relationship with its bank of terminals, means for advancing the selected brush set in a hunting movement over the terminals of its bank, and means rendered variably effective in accordance with which one of said brush sets was rendered operative for governing the extent of said hunting movement.

2. In a selector switch, a plurality of brush sets, banks of terminals associated with said brush sets respectively, the terminals of each of said banks being divided into groups, and said brush sets being normally out of engagement with their associated bank terminals, means for bringing any one of said brush sets into engageable relationship with its bank of terminals, means for advancing the selected brush set in group and terminal hunting movements over the terminals of its bank, and means rendered variably effective in accordance with which one of said brush sets was rendered operative for governing the extent of said hunting movement.

3. In a selector switch, a plurality of brush sets, banks of terminals associated with said brush sets respectively, the terminals of each of said banks being divided into groups and said brush sets being normally out of engagement with their associated bank terminals, means for bringing any one of said brush sets into engageable relationship with its bank of terminals, means for advancing the selected brush set in group and terminal hunting movements over the terminals of its associated bank, an interrupter controlled in the movements of said switch, and means controlled by said interrupter for governing the extent of said hunting movement in accordance with which one of said brush sets was rendered effective.

4. In a selector switch, a plurality of brush sets, banks of terminals associated with said brush sets respectively, the terminals of each of said banks being divided into groups and said brush sets being normally out of engagement with their associated bank terminals, means for bringing any one of said brush sets into engageable relationship with its bank of terminals, means for advancing the selected brush set

in group and terminal hunting movements over the terminals of its bank, an interrupter controlled in the movements of said switch, an auxiliary switch controlled by said interrupter, and means controlled by said auxiliary switch in accordance with which one of said brush sets was rendered effective for governing the extent of said hunting movement.

5. In a selector switch, a plurality of brush sets, banks of terminals associated with said brush sets respectively, the terminals of each of said banks being divided into groups and said brush sets being normally out of engagement with their associated bank terminals, means for bringing any one of said brush sets into engageable relationship with its bank of terminals, means for advancing the selected brush set in group selection and terminal hunting movements over the terminals of its associated bank, an interrupter for said switch having overflow terminals for normally dividing said banks into similar groups, and means rendered variably effective in accordance with which one of said brush sets was rendered operative for rendering at will said overflow terminals effective to change the grouping of the terminals in said banks.

6. In a selector switch, a plurality of brush sets, banks of terminals associated with said brush sets respectively, the terminals of each of said banks being divided into groups and said brush sets being normally out of engagement with their associated bank terminals, means for bringing any one of said brush sets into engageable relationship with its bank of terminals, means for advancing the selected brush set in group selection and terminal hunting movements over the terminals of its associated bank, an interrupter for said switch having overflow terminals for normally dividing said banks into similar groups, and means rendered variably effective in accordance with which one of said brush sets was rendered operative for rendering at will said overflow terminals effective to change the grouping of the terminals in any of said banks.

7. In a selector switch, a plurality of brush sets, banks of terminals associated with said brush sets respectively, the terminals of each of said banks being divided into groups and said brush sets being normally out of engagement with their associated bank terminals, means for bringing any one of said brush sets into engageable relationship with its bank of terminals, means for advancing the selected brush set in group selection and terminal hunting movements over the terminals of its associated bank, an interrupter for said switch having overflow terminals for normally dividing said banks into similar groups, and means rendered variably effective in accordance with which

one of said brush sets was rendered operative for rendering at will said overflow terminals effective to variously change the grouping of the terminals in any of said 5 banks.

8. In a selector switch, a plurality of brush sets each having an off-normal contact, a bank of terminals associated with each brush set, means to selectively render operative a 10 desired one of said brush sets and to operate the associated off-normal contact and means controlled over said contact to determine the grouping of terminals in the bank associated therewith.

15 9. In a telephone exchange system, main groups of trunks divided into sub-groups, the sub-groups of the various main groups being non-symmetrical in capacity, means to select a desired main group and to select a 20 desired sub-group, an auxiliary device, and means to provide for a trunk hunting movement of suitable extent for a selected sub-group, said means being controlled by said auxiliary device in accordance with the main 25 group selected.

10. In a telephone exchange system, main groups of trunks divided into sub-groups, the sub-groups of the various main groups being non-symmetrical in capacity, means to 30 select a desired main group and to select a desired sub-group, an auxiliary device pro-

vided with sections corresponding to each main group, means to render effective a corresponding section of said auxiliary device when a group of trunks is selected, and 35 means to provide a trunk hunting movement of suitable extent for a selected sub-group, said means being controlled at the effective section of said auxiliary device.

11. In a telephone exchange system, a selector switch comprising a contact bank and a plurality of normally inoperative multiple brush sets having access to said contact bank, trunk lines terminating in said contact banks in main groups, there being a main group 40 served by each of said brush sets, sub-groups in each main group, an auxiliary device, means to render operative a desired one of said brush sets to select a main group of trunks, a contact associated with each of said brush sets and operated when a brush set 45 is rendered effective, sections in said auxiliary device corresponding to each main group, means to render effective a desired section when a brush set is rendered operative, and means to determine the maximum extent of the trunk hunting movement of the selector in a selected sub-group under the control of the auxiliary device.

In witness whereof, I hereunto subscribe 50 my name this 18th day of June A. D., 1924.

FRANK N. REEVES.
